UNITED STATES PATENT OFFICE.

NATHAN J. PADDOCK, OF JERSEY CITY, NEW JERSEY.

MACHINE FOR AERIAL FLIGHT.

1,074,135.

Specification of Letters Patent. Patented Sept. 30, 1913.

Application filed August 4, 1911. Serial No. 642,322.

To all whom it may concern:

Be it known that I, NATHAN J. PADDOCK, a citizen of the United States, residing at Jersey City, county of Hudson, and State 5 of New Jersey, have invented certain new and useful Improvements in Machines for Aerial Flight, of which the following is a specification.

This invention relates to machines for 10 aerial flight, and the improvement is applicable to aeroplanes either of the monoplane, or biplane type or any other multi-plane type, or it may also be used in connection with dirigible balloons. It may 15 also be used in connection with gliders.

The main object of the invention is to provide means tending to automatically preserve the center of gravity of such machines so that the work of the aviator is 20 reduced to a minimum, inasmuch as if the machine tends to tilt to one side it is automatically balanced.

Another object of the invention is to provide means for imparting an oscillatory motion 25 to two balancing wings or planes, or to the opposite ends of one plane as in the Wright type of machine, although the invention is applicable to any type of machine.

30 Further objects of the invention are to provide efficient and practical means for automatically preserving the lateral balance of such machines.

These being among the objects of the 35 present invention, the same consists of certain features of construction and combinations of parts to be hereinafter described and then claimed with reference to the accompanying drawings illustrating a suitable 40 form of the invention, and in which—

Figure 1 is a perspective view of so much of a machine for aerial flight as is necessary to illustrate the present improvement; Fig. 2 is a sectional detail view on the line 45 2—2 Fig. 1; the parts being enlarged; and Fig. 3 is a broken horizontal sectional view of said parts, largely in plan, to show clearly the means for holding the pendulum against movement in the direction of flight.

50 Referring to the drawings, the plane frame 1 may be of any suitable construction as it is intended to represent the frame of any machine for aerial flight. The frame is therefore shown of as few parts and as 55 simple as possible, for the purpose of illustrating the invention only and not as de-

fining any particular frame. The frame is provided with an upper support 2 and a lower support or wheel frame 3.

Fig. 1 illustrates balancing wings or 60 planes for preserving the lateral balance of the machine, and which may be made in two separate planes, as shown, to supplement the plane in a monoplane or to supplement the lifting planes in a biplane or multiplane 65 in which the supporting planes are held rigid relatively to each other; or to represent the end portions of the planes in a machine of the biplane or multiplane type in which the supporting planes are warped or 70 moved relatively to the main body of the planes for securing a lateral balancing of the machine. As machines of the Wright type are so well-known, it is obvious that the two planes illustrated in the drawings 75 may represent the ends of a single plane of such type of machine.

The lateral balancing plane which may be composed, as shown of the two end portions 4, 5, will for convenience sake be 80 referred to as one plane as the invention contemplates either two or one such planes. The said plane is mounted on a pivot or hinge rod 6 so that the end sections or portions 4, 5, may be independently moved 85 thereon or adjusted. Any other suitable and obvious means for rendering the end sections or portions of the plane 4, 5, movable may be employed.

For the purpose of maintaining the center 90 of gravity of the machine, a pendulum rod 7 is employed which carries at its lower end a ponderous weight 8 which may be a tool box, gasoline tank, or any weight which will cause the rod 7 to act as a pendulum. Said 95 weight preferably has wedge shaped or tapering edges so as to deflect the air and afford less resistance. The upper end of the pendulum rod has a ball 9 which is received in a socket 10 mounted on the upper support 100 2, and said support is provided with a hole or opening 11 through which the said rod passes, so as to permit the machine to incline if there be any tendency to inclination, as theoretically under the present invention there 105 is assumed to be no substantial lateral movement of the machine, and that the pendulum rod 7 always points toward the center of the earth. Ropes, cords or wires 12, 13, 14 and 15 are attached to the opposite sides of the 110 end portions or sections 4, 5, of the balancing plane, said cords being attached to an auto-

matically movable draft part to be herein-after described.

Between the sides of the lower support or wheel frame 3 there extends a transverse slot 16 which is preferably formed between two transverse cross pieces or slats 17, 18, which support at front and rear and at both sides of the machine, guide pulleys 19 over which the rods, cords or wires 12, 13, 14 and 15 are trained. Referring more particularly to Figs. 2 and 3, the said cords 12, 13, 14 and 15 are connected with the opposite ends of an oscillatory member or lever 20 which is arranged under the cross pieces 17, 18, and is pivoted at its mid-length by pivot 21 to one of the cross pieces, as 18. The lever 20 is acted on by means, through the medium of the pendulum, which tends to maintain said lever in a position directed in the line 20 of flight of the machine. To this end the said lever or oscillatory member 20 is provided with an opening or slot 22 extending longitudinally of the lever and located to one side of the pivot 21. The pendulum rod 25 7 extends through the said opening or slot 22 to a suitable distance below the machine, said pendulum rod also extending through the slot 16, so that the said rod extends through two slots or openings which are arranged at right angles to each other.

It will be seen that under the present invention the pendulum 7, 8, extends toward the center of the earth and that if the machine tilts or tends to tilt laterally, it will 35 be automatically balanced by reason of the lifting of one of the end sections or plane portions, 4, 5, on that side of the machine which tilts or tends to tilt downwardly. This action is accomplished by reason of the 40 vertical position of the pendulum as it is obvious that as the pendulum is theoretically stationary with respect to the vertical axis of the machine, the lateral tilting of the machine will cause the pendulum to move the 45 oscillatory member or lever 20 so as to lift an end section or portion of the plane 4, 5, on that side of the machine toward which the machine tilts. It may be assumed that the machine as viewed in Fig. 1 has tilted 50 downwardly to the left and that the front edge of end section 4 has been raised as indicated by arrow with the simultaneous lowering of front edge of section 5 as indicated. As soon as the said end section or plane 55 portion 4 is lifted by the action of the vertically standing pendulum, it acts to automatically and instantly restore the center of gravity of the machine, because as the machine moves back to upright position, the 60 said plane-end or portion 4 will, in moving back to normal position, act to restore the said lever or member 20 to position by its action upon the cord or rope at the opposite side of said plane. If the machine tilts or 65 tends to tilt to the other side, the lateral

balance is preserved and the center of gravity is restored in a similar manner.

There may be times when it is desired to lock the pendulum to the machine, and to this end a locking slide 23 is provided, which is guided longitudinally of the line of flight of the machine by means of cleats or guides 24 located on the cross pieces 17, 18. Said slide may be moved by any suitable operating means within convenient reach of the aviator. It is provided with a preferably diamond shaped aperture 25 through which the pendulum rod 7 extends, and at the opposite ends of said aperture in the direction of the length of the slide there are notches 26. These notches are of such dimensions that if this slide is moved endwise a suitable distance, one of the notches will engage the pendulum rod frictionally and lock the pendulum against movement. The diamond shape of said aperture 25 regulates the lateral movement of the pendulum if there be any, the amount of regulation depending upon the position to which the slide is adjusted.

A rope 27 is provided which is attached at its lower end to an eye or loop 28 on the upper end of the pendulum, and said rope is guided over a pulley 29 mounted at the upper part of the frame 1. Said frame is 90 provided with a hook 30 so that when the upper end of the rod is pulled up for a sufficient distance, the pendulum will be raised and its eye 28 may be engaged with the hook 30. This lifting means is for the 95 purpose of elevating the pendulum when its action is not desired, and for holding its ponderous weight 8 up far enough so that it will not strike the ground when the machine strikes it, as the wheels will strike 100 first.

What I claim as new is:—

1. An aerial machine comprising an upper support, a lower support, an open frame mounted on the lower support, a locking slide mounted on the frame and having an aperture, and a pendulum suspended from the upper support and extending through the aperture and through the opening of said frame.

2. An aerial machine comprising an upper support, a lower support, a transverse frame having a slot and mounted on the lower support, a locking slide mounted on the transverse frame and having a central aperture and end recesses and a pendulum suspended from the upper support and extending through the central aperture and through the slot.

3. An aerial machine comprising a plane frame, an upper support, a pendulum supported from the upper support, means controlled by said pendulum and located beneath said upper support, means for raising and lowering the pendulum from the plane-

frame and for moving it vertically through said controlled means, and means for suspending the pendulum from the frame.

4. An aerial machine comprising a plane frame, an upper support, a pendulum having means whereby it is suspended from the upper support, and provided with an eye, a guide suspended from the plane-frame, a supporting hook for engaging the eye of the pendulum, and a flexible connection for raising and lowering the pendulum and for engaging the said eye with said hook.

5. An aerial machine comprising a plane-frame, an upper support, a pendulum having a head, whereby it is suspended from the upper support, provided with an eye, a pulley suspended from the plane-frame, and having a supporting hook for engaging the eye of the pendulum head, and a flexible connection for raising and lowering the pendulum on the pulley.

6. An aerial machine comprising supporting parts, a frame thereon having a plane and a slot extending transversely of the machine, a lever pivoted to said frame and having a slot extending across said transverse slot, flexible connections extending from the plane to the lever, and a pendulum sus-

pended from the upper support and extending through the crossed slots.

7. An aerial machine comprising supporting parts, a frame thereon having a plane and a slot extending transversely of the machine, a lever pivoted to said frame and having a slot extending across said transverse slot, an open slide, flexible connections extending from the plane to the lever, and a pendulum suspended from the upper support, and extending through the crossed slots and through the opening of said slide.

8. An aerial machine comprising a plane-frame having a plane, an upper support, a lower support, a transverse frame having a slot and mounted on the lower support, a lever having a slot and extending across the slot of the transverse frame and pivoted to the transverse frame at one side of the slot of the transverse frame, flexible connections extending from the plane to the lever, and a pendulum suspended from the upper support and extending through the crossed slots.
